UNITED STATES PATENT OFFICE.

HENRY C. ATKINSON AND WILLIAM MILLER, OF LOUISVILLE, KENTUCKY.

DESIGN FOR A CUSPIDOR.

SPECIFICATION forming part of Design No. 24,173, dated April 2, 1895.

Application filed December 31, 1894. Serial No. 533,456. Term of patent 3½ years.

To all whom it may concern:

Be it known that we, HENRY C. ATKINSON and WILLIAM MILLER, citizens of the United States, residing at Louisville, in the county of Jefferson and State of Kentucky, have invented and produced a new and original Design for a Cuspidor; and we do declare the following to be a full, clear, and exact description of the same, reference being had to the accompanying drawings, forming a part thereof.

Figure 1 is a perspective view of a spittoon showing our design. Fig. 2 is a transverse sectional view of the same necessary to illustrate our design.

The leading feature of our design consists of a cuspidor having a crescent shaped guard or visor attached to the top of the bowl and projecting above the same.

The bowl is formed of two portions A and A' each larger at one base than the other, as shown, the portion A' having its larger base closed by a bottom a. The two portions are joined at their smaller bases. A belt B, corrugated, appears at the point of junction of the two parts A and A'. The diameter of the lower portion A' at its bottom is slightly greater than the top diameter of the portion A.

What we claim is—

The design for a cuspidor, substantially as herein shown and described.

In testimony whereof we affix our signatures in presence of two witnesses.

HENRY C. ATKINSON.
WILLIAM MILLER.
